UNITED STATES PATENT OFFICE.

HERMAN A. SCHULTZ, OF BERKELEY, CALIFORNIA.

AUTOMATIC ELECTRIC SWITCH.

SPECIFICATION forming part of Letters Patent No. 792,734, dated June 20, 1905.

Application filed January 3, 1905. Serial No. 239,333.

To all whom it may concern:

Be it known that I, HERMAN A. SCHULTZ, a citizen of the United States, residing at Berkeley, in the county of Alameda and State of California, have invented new and useful Improvements in Automatic Electric Switches, of which the following is a specification.

My invention relates to an apparatus by which pumps and other machinery may be automatically set in motion or their operation discontinued through the medium of an electric current.

My invention consists in a combination of parts and mechanism and in details of construction, which will be more fully explained by reference to the accompanying drawings, in which—

Figure 1 is a view showing the float depressed and the switch open. Fig. 2 shows the float raised and the switch closed. Fig. 3 is a general view showing a motor-pump and electric and hydraulic connections which may be used in connection with my invention.

It is the object of my invention to provide a simple practical form of electrical circuit-closing mechanism which is applicable for use particularly in the pumping of water, such as in cellars, basements, mines, and other places where flooding or overflow is liable to occur and where the rise and fall of the water will start or stop a suitable pump or equivalent apparatus for reducing the amount.

It will be manifest that various forms of mechanism may be used to produce the required result. In the present case I have shown a frame A, having vertical guides, as at 2, and upon these guides a frame 3 is adapted to slide. This frame carries a float 4 of any suitable shape or size, and this float is 40 slidable with the frame 3 between the guides 2 and has also a limited movement within the frame 3, which is independent of the movement of said frame. Under ordinary conditions the frame of the float will rest at the 45 bottom of the guides contiguous to the floor or the depression or sump in which the water may collect and from which it is to be pumped. In case of an increase in the water the float will gradually rise until it contacts with a suitable 50 stop or cross-bar upon the upper part of the

frame 3. This frame will then be lifted by the float and thereafter move in unison therewith if the water continues to increase. The movement of the float and frame are contrived by suitable connections to operate a switch 55 by which an electrical circuit may be closed or opened. This switch mechanism is formed as follows: Extending upward from the frame 3 is a rod 5. This rod connects with a lever 6, fulcrumed to a suitable support, as at 7. 60 One end of this lever carries a roller 8, which is adapted to ride over the converging inclined sides of a block 9, having a guided 65 slide shank, as at 9^a, and normally pressed forward into contact with the roller by a spring, as at 20. The other end of the lever 6 is connected, by means of a link 10, with a carriage 11, slideable upon suitable guides, as at 12. The carriage supports one member 13 of a knife or equivalent switch, which may be 70 moved into or out of contact with the other member 14 of said switch. The upper end of the rod 5, where it connects with the lever 6, is slotted, as shown at 15, and the upper end of the link 10 is similarly slotted, as at 16, both of these slotted ends being slideable over pins which connect them, respectively, with the lever 6 and with the slideable frame 11. The object of these slots is to provide 75 for a suitable amount of movement of the float before the switch is closed during the rising of the float and, similarly, a considerable movement downward of the float without separating the switch members and cutting off the electrical current. 80

The operation of the apparatus will then be as follows: The float 4 and frame 3 being at the lowest point, resting substantially at the bottom, the lever 6 will be drawn downward, and the roller 8 will press against the upper 90 incline of the wedge-shaped block 9. The tension of the spring 20 will cause this inclined surface to press against the roller, so as to pull the rod 10 downward, so that the pin connecting it with the carriage 11 will be at 95 the upper end of the slot 16. The float and frame 3 being also at their lowest point, the slot 15 will also be in such position that the pin connecting it with the lever 6 passes through the upper part of the slot. Any rise in the wa- 100

ter will commence to lift the float, which continues to rise until it contacts with the stops on the frame 3, when this frame will also rise. As soon as the bottom of the slot 15 comes in

5 contact with the pin connecting it with the lever 6 this lever will also begin to move and will simultaneously move the rod 10, which by reason of its slotted upper end will slide upon the pin connecting it with the carriage 10. 11. As soon as the movement of the parts has reached a point where the roller 8 passes over the apex of the wedge-shaped block 9 the action of the spring will suddenly move the lever through the remainder of its travel 15 and independent of the further movement of the float, and thus the switch will be rapidly closed and the circuit completed. The slots 15 and 16 allow of this sudden independent movement. As soon as the circuit is closed an 20 electrical current will pass through from any suitable source of electrical energy and may be made to operate a motor M, as shown in Fig. 3, which through a drive-belt or other means will operate a pump P, with an inlet- 25 pipe P' reaching into the pump and an outlet-pipe P² carrying the discharge aboveground, as shown in Fig. 3. This is only one of many constructions which may be used in connection with my invention. In case of the pump 30 it will operate to decrease the body of water, and the float will gradually lower until first the top of the slot 15 comes in contact with the pin connecting it with the lever 6, and this movement will gradually turn the lever 35 about its fulcrum-point until the roller 8 has again passed the apex of the wedge-shaped block. The rod 10 will also have been drawn down until the upper end of the slot 16 is approximately in contact with the pin which 40 connects it with the carriage 11. At this instant, the roller 8 having passed the apex of the block 9, the tension of the spring 20 will act to force the block out, and the incline traveling beneath the roller 8 moves the lever 45 suddenly to the full extent of its throw in the direction in which it is started, thus suddenly disconnecting the switch members 13 and 14 and cutting off the electrical current.

Various adjustments of the parts may be 50 made. The connection between the frame 3 and the lever 6 may be made by means of a two-part rod 5 and 5^a, one part having a guide within which the other part is movable, and by means of a set-screw or other equivalent lock, as at 21, these two parts may be firmly united and any lengthening or shortening made to adjust the movements of the float and its frame to those of the lever, switch, and connecting parts. The tension of the spring 55 20 may also be regulated by means of a nut, as at 23, moving upon a screw-threaded spindle and a plate bearing against the spring.

The length of the slots 15 and 16 is sufficient to permit the float to sink to a considerable distance without moving the connecting

parts or disengaging the switch, so that the level of the water will be lowered to any desired extent before the pump-actuating power is thrown out of action.

Having thus described my invention, what I claim, and desire to secure by Letters Patent, is—

1. The combination with an electric switch, of a float, a fulcrumed lever, connections between the float and the lever, connections between the lever and a movable member of the switch, and a wedge-shaped yieldable member against which one end of the lever is traversable. 75

2. An electrical switch comprising a fixed and a movable member, a carriage to which the movable member is attached, a fulcrumed lever, a connection between one end of said lever and the carriage, a float adapted to rise and fall, connections between said float and the lever, said connections between the said lever and the carriage and the float, being slotted to allow an independent movement of the float in either direction without moving the switch member, and a spring-pressed member bearing against the lever and by which the movement of said lever is accelerated. 85 90

3. An electrical switch comprising a fixed and a movable member, a carriage for the movable member, a fulcrumed lever, a slotted bar connected with one end of the lever and with the carriage of the movable member, a float, a rod connecting the float with the lever, an antifrictional device carried by the end of the lever upon the opposite side of its fulcrum, and a wedge-shaped spring-pressed block against which said end of the lever is movable. 95 100

4. An electrical switch comprising a fixed and a movable member, a fulcrumed member having one end loosely connected with the movable member of the switch and with a rising and falling float, a transversely-slidable spring-pressed wedge-shaped block, an antifrictional device carried by the end of the lever adapted to contact with said block whereby the movement of the lever is accelerated at the instant when its end passes the apex of the block. 105 110

5. An electrical switch comprising a fixed and a movable member, a fulcrumed lever, a float movable substantially in line with the movement of the switch member, a loose connection between the float and the lever, a second loose connection between the lever and the movable switch member and an inclined or wedge-shaped block, a roller carried by the end of the lever adapted to contact with the inclined faces of the block, a spring acting to force the block against the lever and to accelerate the movement of the lever and the closing or opening of the switch when the roller has passed the apex of the wedge-block. 115 120 125

6. In an electrical-switch-actuating mechanism, a guided slideable float, a guided and 130

slidable frame within which the float is independently movable, contacts by which the float acts to move the frame at certain points of its rise or fall, a fulcrumed lever, connections between the float-frame and one end of said lever, an electrical switch comprising a fixed and a movable member, connections between the lever and the movable switch member and a spring-pressed wedge-shaped block acting against the opposite end of the lever to accelerate its motion and that of the switch member when the lever end has passed the apex of the block.

7. In an electrical-switch-actuating mechanism, a guided rising and falling float, a similarly-guided yoke or frame within which the float has a limited movement, a fulcrumed lever, a slotted-rod connection between one end

of the said lever and the slidable frame, an electrical switch having fixed and movable members, a slotted-rod connection between the lever and the movable switch member, an antifrictional roller carried by the opposite end of the lever, a movable spring-pressed block having double inclined surfaces pressing against the roller, said surfaces acting to suddenly complete the movement of the lever in either direction after the roller has passed the apex.

In testimony whereof I have hereunto set my hand in presence of two subscribing witnesses.
